(57) **CLAIM**

The ornamental design for a handle module, as shown and described.

DESCRIPTION

FIG. 1 is a top, front, left side perspective view of a handle module showing my new design;

FIG. 2 is a bottom, back, right side perspective view thereof; FIG. 3 is a front view thereof, the back view being a mirror image thereof;

FIG. 4 is a top view thereof;

FIG. 5 is a bottom view thereof; and,

FIG. 6 is a left side view thereof, the right side being a mirror image thereof.

FIG. 7 is a top, front, left side perspective view of a handle module showing a first alternate new design;

FIG. 8 is a bottom, back, right side perspective view thereof;

FIG. 9 is a front view thereof;

FIG. 10 is a back view thereof;

FIG. 11 is a top view thereof;

FIG. 12 is a bottom view thereof; and,

FIG. 13 is a left side view thereof, the right side being a mirror image thereof.

FIG. 14 is a top, front, left side perspective view of a handle module showing a second alternate new design; the bottom, back, right side perspective view thereof being the same as FIG. 8;

FIG. 15 is a front view thereof; and,

FIG. 16 is a back view thereof; the top view thereof being the same as FIG. 11; the bottom view thereof being the same as FIG. 12; the left side view thereof being the same as FIG. 13; the right side being a mirror image of FIG. 13.
